OIL PUMPING APPARATUS

Gunnar C. Engstrand, New York, N. Y., and Charles A. G. Armstrong, Roselle, N. J., assignors to Sludge Pumping, Inc., New York, N. Y., a corporation of New York

Application September 2, 1933, Serial No. 687,930

4 Claims. (Cl. 103—5)

Our invention relates to a method and apparatus for the pumping of heavy oil sludges and residues. These sludges are usually extremely viscous and stable watery emulsions and resist all attempts of pumping by ordinary pumping methods.

There have been numerous attempts made to pump such viscous residues by steam jet pumps, but these attempts have hitherto resulted in failure, inasmuch as ordinary steam jet pumps will not handle such viscous material. We have however discovered that steam jet pumps of a modified construction and combined with a swing check valve placed in front of and at some distance from the steam jet pump will not only pump the viscous material from the bottom of storage tanks where it accumulates, but will also effectively handle all kind of viscous oils, semi-liquids and liquids and deliver the pumped material over considerable distances and elevations without reducing the pumping rate below the one required for practical consideration.

Now therefore our apparatus is especially adapted for the removal of the residue accumulations which periodically accrue at the bottom of oil burning vessels, and as our apparatus only includes a small portable steam ejector, readily hooked up to the steam plant of the vessel itself, and some flexible hose lines, no special floating equipment is required for its installation and a most inexpensive periodical or occasional sludge removal may be accomplished by our apparatus.

As during our pumping air is also withdrawn from the storage tanks, the highly explosive gases which are generated by the oily residues are effectively removed during the pumping and all danger of explosion averted.

We have found that air which is sucked into the transmission line by the relatively low vacuum that is created by our steam jet pump will cause the material to travel through the suction line in form of a wave or short slug which seals the suction line during its travel therethrough.

We have discovered that the diameter of the pump intake proper must be considerably smaller than that of the suction hose and also that in order to achieve a practical and positive pumping rate it is imperative in some manner to trap the sealing slug just in front thereof. As the slug is approximately three to four feet long, we prefer to accomplish the trapping by a conventional swing check valve placed in front of the pump intake and at a distance of approximately two feet therefrom.

Finally we have found that heating of the pump intake by a steam jacket assists the pumping as such heating considerably reduces the throat friction in the pump.

Our invention specifically relates to a certain grouping together of known elements, and accomplishes that which hitherto was considered impossible to achieve without the use of giant machinery entirely out of proportion with the work accomplished.

A successful and economic pumping performance therefore requires a number of steps to be taken in order to arrive at a desired result and we therefore claim as invention these steps as constituting a method.

We also claim as invention the grouping together of old elements by means of which arrangement we achieve new and novel results.

In the drawing:—

Figure 1 shows our preferred apparatus removing the viscous residue from the interior of a maritime vessel and discharging the same into a slop barge moored at the side of the vessel.

Figure 2 shows an enlarged view of our preferred assembly of parts.

Figures 3 and 4 show the detail construction of our preferred steam jet pump.

In the drawing where like reference characters denote corresponding parts; 1 denotes the ship from the double bottom of which the viscous material 2 is removed and pumped into the slop barge 3 which is shown moored at the ship's side.

On the deck of the slop barge 3 the boiler 4 is installed, which furnishes the steam to the steam jet pump 5 by means of the steam hose 6.

The steam jet suction pump 5 is shown with one end connected to the swing check valve 7 by means of the nipple 8, and the other end to the discharge hose 9 by means of the reducer 10.

A suction hose 11 is attached to the swing check valve 7 and led into the double bottom of the vessel 1 and the end thereof is shown dipped into the sludge 2 which is to be pumped into the slop barge 3.

The steam jet pump 5 is of the annular jet design with a central passage for the material and comprises a castiron body provided with enlarged socket ends 13 and 14, and a tapered and cored nozzle piece 15 so as to form a steam jacket 16 having a circular opening 17 around the hollowed core 18 which allows for the passage of the material.

The steam jacket 16 is provided with the steam inlet 18' to which the steam line 6 is connected, and the valve 12 controls the steam supply from

the boiler. The nozzle piece 15 is provided with a tapered end 19 and the taper thereof is more pronounced than that of the iron body of the jet pump. Now therefore this steam nozzle is an 5 expanding nozzle, the steam being allowed to expand to a considerable degree before it enters into the iron body of the pump.

The operation is as follows:—

The discharge hose is swung over the ship side

10 and the steam jet pump is preferably placed on top of the double bottom of the vessel.

The steam operating valve is opened and the suction hose is led into the tank and there dipped into the material to be pumped, care being taken 15 at all times to so hold the intake end so that atmospheric air is free to enter into the transmission line together with the material.

The material is sucked up by the relatively low 20 vacuum created by the steam jet issuing from the annular jet opening and moves through the suction line in a wave or slug formation and only one slug at a time passes into the system.

Now however, as the area of the intake proper 25 of the pump in our preferred apparatus is less than one-third of the area of the suction hose, the sealing slug will be effectively arrested at the narrow intake of the jet pump just before it comes in contact with the steam jet and is there positively trapped by the swing check valve, and 30 the steam will therefore strike a solid column of liquid material which passes through the pump.

It is to be noted that we employ a discharge line nearly double in area of the suction line, and due to this arrangement the slug which is intermittently discharged by the pump will have a 35 diameter much smaller than the discharge line and will therefore be effectively suspended in the surrounding steam and a practically frictionless and rapid discharge of the slug through the line 40 is accomplished.

It is also to be noted that the outside of this 45 liquid column is heated by the steam jacket which surrounds the intake of the pump and said pre-heating will considerably assist the pumping, inasmuch as it considerably reduces the friction set up between the narrow pump intake and the viscous material. As this friction has to be overcome by the suction of the jet pump and as it is 50 a well known fact that a suction head corresponding only to a couple of feet liquid head does reduce the capacity of a steam jet to practically half as compared with the capacity thereof when there is no suction head at all, it is most important to reduce the suction head of our pump to a 55 minimum.

A vacuum gauge placed at the check valve in a full size commercial apparatus shows a regular 60 vacuum variation from zero to 10 or 11 inches approximately every 6 seconds and the check valve clicks shut for each period of variation.

Now, therefore, what we accomplish by our 65 method is the intermittent transfer of the material to the intake proper of the pump and the discharge of the material through the pump with a minimum of suction head, as the pump suction is broken in the suction line during the slug discharge.

The first step of our pumping method is therefore 70 the admitting of air to the suction end and the creating of an intermittent and moderate vacuum to thereby suck the material through the suction line in a slug formation.

The second step is the simultaneous arresting and trapping of the slug at the intake end proper of the pump together with the preferred surface heating of the slug. The third step is the ejection of the material through the discharge hose in form of a slug suspended in the steam stream therethrough.

We have operated our apparatus at commercial work over lifts in excess of forty-five feet.

We have invariably found that when air is 80 admitted at the intake end of the system only one slug at a time passes through the transmission hose.

We are not limiting our claims for invention to the apparatus shown as it is obvious that modification may be made in the adaptation of our device without departing from the spirit and scope of our invention.

We claim:—

1. The method of pumping viscous material 25 through a transmission line characterized by creating a steam stream through the discharge portion of the line so as to create a moderate vacuum in the intake portion thereof, admitting air and material at the suction end to cause a slug to 100 travel singly through the suction portion of the line, arresting the slug at the end thereof so as to break the vacuum therein and discharging this slug suspended in the steam stream through the discharge portion of the transmission line. 105

2. The method of pumping viscous material through a transmission line characterized by creating a steam stream through the discharge portion of the line so as to create a moderate vacuum in the intake portion thereof, admitting 110 air and material at the suction end to cause a slug to travel singly through the suction portion of the line, arresting the slug at the end thereof so as to break the vacuum therein, trapping said arrested slug and discharging this slug suspended 115 in the steam stream through the discharge portion of the transmission line.

3. The method of pumping viscous material through a transmission line characterized by creating a steam stream through the discharge 120 portion of the line so as to create a moderate vacuum in the intake portion thereof, admitting air and material at the suction end to cause a slug to travel singly through the suction portion of the line, arresting the slug at the end thereof 125 so as to break the vacuum therein, heating the surface of said arrested slug and discharging this slug suspended in the steam stream through the discharge portion of the transmission line.

4. The method of pumping viscous material 130 through a transmission line characterized by creating a steam stream through the discharge portion of the line so as to create a moderate vacuum in the intake portion thereof, admitting air and material at the suction end to cause a slug to 135 travel singly through the suction portion of the line, arresting the slug at the end thereof so as to break the vacuum therein, trapping said arrested slug, heating the surface thereof and discharging this slug suspended in the steam stream 140 through the discharge portion of the transmission line.
